UNITED STATES PATENT OFFICE.

WILLIAM J. LANKFORD AND WALTER H. CHAPPELL, OF CHANUTE, KANSAS.

CONCRETE RAILWAY-TIE.

1,387,547.

Specification of Letters Patent. Patented Aug. 16, 1921.

Original application filed October 30, 1920, Serial No. 420,605. Divided and this application filed March 14, 1921. Serial No. 451,967.

To all whom it may concern:

Be it known that we, WILLIAM J. LANKFORD and WALTER H. CHAPPELL, citizens of the United States, residing at Chanute, in the county of Neosho and State of Kansas, have invented certain new and useful Improvements in Concrete Railway-Ties, of which the following is a specification.

This invention seeks to provide an improved concrete railway tie that embodies a plurality of sections in endwise alignment adapted for being readily assembled or connected in operative condition and which are especially designed for convenient connection with means tending to so connect the body sections that the ready removal and renewal of the said parts may be expeditiously and practically accomplished.

More specifically our present invention 20 has reference to improved features relating to the special type of concrete tie disclosed in our copending application, Serial No. 420,605, filed October 30, 1920, of which this application is a divisional part, and 25 our said present invention embodies certain peculiar features of construction and modifications of the form of rail tie disclosed in our copending application, all of which will be fully explained in the following detailed description, specifically pointed out 30 in the appended claims and illustrated in the accompanying drawing in which:

Figure 1 is a top plan view of our present construction of concrete tie, the longitudinal and transverse reinforce members herein-after referred to, being indicated in dotted lines.

Fig. 2 is a partial longitudinal section of one end of our present construction of concrete tie.

Fig. 3 is a transverse section thereof taken on the line 3—3 on Fig. 1.

Figs. 4 and 5 are respectively a top and a bottom perspective of the tie plate herein-after referred to.

Fig. 6 is a detail view of a modification of the rail brace member hereinafter mentioned.

In the drawings, in which like numerals 50 designate like parts in all of the figures and referring more particularly to Figs. 1, 2 and 3, the body portion of the tie consists of two half sections 1—1 that are disposed end to end and in longitudinal alignment and, in 55 the practical development of our concrete

tie, the outer end of each of the sections 1 preferably has a clover leaf or lobe shape, as shown in Fig. 1, the opposite sides and end faces of the body being vertical and provided with panels or recesses for the 60 convenient handling of the said body sections, when placing them in their co-operative position or removing them when necessary.

Each tie section 1 has a countersunk recess 3 at its inner end and such recesses 3, when the tie sections are placed end to end, form a space into which is received a cushioning block 4 whose purpose is to take up and intercept vibration of the tie body and 70 avoid the effect of rigidity of the tie.

In our present construction of tie, the rails 10—10 do not rest directly upon the top of the tie but seat on metal plates 5 which are hereinafter termed "tie plates", 75 the application of which and the means for holding them securely upon the top of the tie section 1 and the clamping devices that co-operate therewith, being best shown in Fig. 3.

By referring to the said Fig. 3, and to Figs. 4 and 5, it will be noticed the plate 5 has a central recess 50 at the outer edge thereof and at the opposite edge it has a centrally disposed aperture 51, the purpose 85 of which will presently appear, it also having along the said opposite edge, other apertures 6—6 each of which is designed for receiving a clamp bolt 7, the latter serving as spikes for clasping over the adjacent 90 base flange of the rail, as is best shown in Fig. 2.

Each bolt 7 has an angled portion 70, at its lower end, for engaging with a reinforcement plate which extends under a draw rod 95 9 whose outer end adjustably carries a clamping device adapted for engagement with the base flange and the web of the adjacent rail, as will be presently more fully explained.

In the present arrangement of our cement tie and rail clamping means, cushion members 11 are also included that seat under the plates 5, as shown in Figs. 2 and 3, and the outer edges of the said members are 105 shaped to straddle the clamping device on the outer end of the draw rod 9, as is clearly indicated in Fig. 2.

The inner ends of the cushion members are secured by the spike bolts 7—7 that pass 110

down through the said inner ends thereof, which ends are securely held down by the tie plates 5 and the upper clamping ends 12^a of keepers 12, presently further referred to, and the outer ends of the said plates 11 are notched to straddle the rail clamping ties on the outer end of the rod 9, as shown in dotted lines, Fig. 2.

The keepers 12, before referred to, are 10 embedded in the cement sections and each of the said keepers has an inturned hook 12^a that fits over the outer edge of an adjacent tie plate 5 one being located at each side of the rail clamping device to be presently explained, the said keepers 12 in addition to holding the plate 5 serving to also avoid spalling of the concrete at the outer edges of the said tie plates.

In the preferred arrangement of the rail 20 clamping means, two opposite draw rods 9—9 are joined by a turn buckle connection 17, as shown and described, and the outer end of each draw rod 9 is provided with a rail clamping device, one of such devices 25 being shown in detail in Fig. 2, which illustrates the said device as consisting of a combined clamp and anchor device 30 which includes a base that seats and has longitudinal adjustment within the outer end of the 30 groove or channel 16 that extends through the end of the tie, the fit of the clamp base within the groove being such that the clamp is held against tendency of lateral displacement.

35 The base of the clamp 30 has a passage for slidably engaging the outer threaded end 96 of the draw rod 9 and it is adapted to be closely drawn up against the face of the adjacent rail end by an adjusting nut 33.

40 While we prefer to use two draw rods 9—9 with a turn buckle connection 17, as is shown and described, it should be mentioned that when the rail clamp devices 30 are arranged as described and shown but a single 45 draw rod 9, extending practically the full length of the tie may be used and the turn buckle devices 17 may be dispensed with since the combined clamp and anchor devices 30 will keep the rails from tilting or spreading.

50 Instead of arranging the combined clamp member 30, as shown in Fig. 2, the said rail engaging means may be as shown in the slightly modified arrangement illustrated in 55 Fig. 6, which shows a supplemental brace member 19 which is adapted for engaging the rail web directly under the head or tread portion thereof, and which includes a pendant or base portion 19^a that is apertured to 60 slidably fit upon the threaded end 96 of the draw bar 9 and which is held up to the clamping position, with the clamp 30, by a nut 33, as shown.

65 In the practical application of our present form of rail tie, the same is provided

with headed studs for engaging with slotted ways 61 in the vertically adjustable wings or shields provided to prevent waste of the filling while tamping at the ends of the tie, particularly when the ends are 70 concaved on their under side as shown by dotted lines in Fig. 2, and while we have not described or shown the same in this application, the tie ends may be further reinforced by vertical and horizontal tie rods, 75 as fully explained and shown in our co-pending application before referred to.

It is understood that the specific arrangement of the parts that constitute our present type of rail tie and rail clamping means 80 may be further modified or varied without departing from the scope of the appended claims.

What we claim is:

1. In a railway tie of the character stated, 85 two body sections in end to end relation, means for holding the said sections in such relation, a tie plate located at the outer end of each tie body section, means for fixedly holding the said plates down on their respective tie body ends, the said plates constituting the bearings onto which the rails are placed, means including gripping elements for clamping the outer base flange of the rails, other means for clamping the inner flanges of the rails, the said outer flange clamping means including devices for drawing up the clamping elements against the outer base flanges of the rails and devices 90 connected with the tie plates upon which the rails seat for holding the inner rail base flange clamping members in locked engagement with the said inner rail flanges.

2. In a railway tie structure, two body 95 sections, means for holding said sections in endwise relation, other means embedded in each tie section for engaging the inner flanges of the rails, further means for engaging the outer flanges of the rails, the said further means comprising a cross bar having its opposite ends extended under the opposite rail members and clamps adjustably mounted on said opposite ends of the cross bar, the said clamps having portions for engaging and forcing the rails against the inner rail 100 flange clamping means.

3. In a railway tie structure, two body 105 sections, means for holding said sections in endwise relation, other means embedded in each tie section for engaging the inner flanges of the rails, further means for engaging the outer flanges of the rails, the said further means comprising a cross bar having its opposite ends extended under the opposite rail members and clamps adjustably mounted on said opposite ends of the cross bar, the said clamps having portions for engaging and forcing the rails against the inner rail 110 flange clamping means, and supplemental 115 adjustable members on the said

threaded outer ends of the cross bar adapted for engaging the web of the rail and the under side of the head or tread portion thereof.

- 5 4. In a railway tie structure, two body sections, means for holding said sections in endwise relation, other means embedded in each tie section for engaging the inner flanges of the rails, further means for engaging the outer flanges of the rails, the said further means comprising a cross bar having its opposite ends extended under the opposite rail members and clamps adjustably mounted on said opposite ends of the cross bar, the 10 said clamps having portions for engaging and forcing the rails against the inner rail flange clamping means, said bar being formed of two opposing sections and a turnbuckle connection that joins the adjacent 15 ends of the said opposing sections.
5. In a railway tie structure, two body sections, means for holding said sections in endwise relation, means for holding the adjacent ends of the said sections in rigid relation, a draw rod lengthwise of the upper face of the tie and whose opposite ends extend under and beyond the opposite rails and rail clamping means for each end of the rod, each of the said means being longitudinally 20 slideable along its corresponding

end on the draw rod, the said clamping means including a portion that constitutes a clamp for engaging the rail base for holding the said rail down on the tie and a brace portion that engages the web of the 35 rail under its head.

6. In a railway tie structure, the combination with one end of the tie and a rail mounted transversely on the said tie end; of means for holding the said rail from moving in the direction of the length of the tie, the said means comprising clamping members secured at their lower ends within the tie body and having their upper ends adapted for clamping onto the inner flange of the 40 rail, a draw rod having an outer threaded end, the said rod extending lengthwise of the tie and under the rail, a clamp slidably 45 engaging with the outer threaded end of the said rod and provided with a member for clamping the outer flange of the rail, and an upwardly and inwardly extending brace member adjustable lengthwise of the tie and having a member for engaging the web of the rail at the underside of the rail head, and 50 means for effecting adjustment of and holding the draw rod to its adjusted positions. 55

WILLIAM J. LANKFORD.
WALTER H. CHAPPELL.
